UNITED STATES PATENT OFFICE.

NILS GUNNAR PALMGREN, OF STOCKHOLM, SWEDEN, ASSIGNOR TO ALLMÄNNA TELEFONAKTIEBOLAGET L. M. ERICSSON, OF DOBELNSGATAN, STOCKHOLM, SWEDEN.

AUTOMATIC AND SEMIAUTOMATIC TELEPHONE EXCHANGE.

Application filed December 22, 1923. Serial No. 682,184.

To all whom it may concern:

Be it known that NILS GUNNAR PALMGREN, a subject of the King of Sweden, residing at 14 Varvsgatan, Stockholm, Sweden, has invented certain new and useful Improvements in Automatic and Semiautomatic Telephone Exchanges, of which the following is a specification.

The invention relates to automatic and semiautomatic telephone-exchanges, in which the selective operation of the numerical selectors is controlled by a register equipment which has been previously set in accordance with the number of the wanted subscriber by means of current impulses sent from the subscriber's station or an operator's position respectively. The object of the invention is to prevent disturbances and wrong connections which may be caused by the numerical selectors and the register switches not operating exactly in the same tempo what may occur for instance when the numerical selectors operate at a great speed, in which case one or more of the current impulses sent to the register switches may be lost. It may also occur that the time intervals between the current impulses is too short to allow the stopping device of the numerical selectors to operate exactly in the right moment, thus causing the selector to pass the contact position in question. In accordance with this invention said inconveniences are overcome by the current impulses for setting the numerical selectors and the register switches being sent alternately from the register switch to the selector and from the selector to the register switch, over circuits which are controlling one another in such a way that the selector cannot be set into a new position until the register switch has been advanced into a corresponding position.

Another object of the invention is to attain a great speed of operation of the numerical selector and the register switches notwithstanding said mutual control which otherwise might cause some delay in the switching operation. To this end a particular kind of selector switches and, contingently, also register switches are used in accordance with this invention, which are so devised as to be advanced two steps for each current impulse, viz, one step upon the closure of the impulse circuit and another step upon the opening of the impulse circuit. In

using such switches preferably only every second position of the switch is used for numerical designation, the intervening positions being utilized for sending out control impulses to the register equipment or the selector respectively.

The invention is not limited to systems using mechanical selectors and register switches as switches made up entirely of relays may also be used. Primarily, however, the invention contemplates the use of mechanical switches and, particularly, switches of the kind which are driven during the selective operation by spring power or the like and which are stopped in different positions of adjustment by means of a holding magnet. It has proved in practice that switches of this type are capable of a considerably quicker operation than such electro-mechanical switches in which the electro-magnet forms at the same time the propelling device of the switch.

The invention will be more closely described with reference to the accompanying drawings. Fig. 1 is a simplified circuit diagram illustrating the principle of the invention. Fig. 2 shows the construction of the numerical selector switches. Figs. 3-8 represent a complete circuit diagram for a talking connection in a semiautomatic telephone-exchange according to the invention, Fig. 3 showing the line finders and the pre-selectors, Fig. 4 one of the first group selectors and the appertaining junction finder and sequence switch, Fig. 5 the register finder, the register equipment and the appertaining control switches, Fig. 6 one of the second group selectors and the appertaining junction finder and sequence switch, Fig. 7 the connector and the appertaining sequence switch, and Fig. 8 the line selector and the appertaining selector finder and switching relays.

In Fig. 1 FL_1 designates a junction line leading into the first group selecting section, said junction line being connected to the subscriber's line in known manner by means of a line finder and a pre-selector. The figure shows schematically three register switches RE_1 , RE_2 , RE_3 forming together a register equipment REG . A number of such register equipments are accessible in common to a group of junction lines FL_1 over register finders RSG , one such register finder being allotted to each junc-

tion line FL_1 . The successive connecting of the different register switches to the junction line FL_1 or the numerical selector RV respectively is effected by means of a primary register controller PRO and a secondary register controller SRO respectively. Connected to the junction line FL_1 is an impulse relay RS adapted to be included in the subscriber's line circuit and to transmit 10 the impulses from the subscriber's station to the register switches.

The construction of the numerical selector RV schematically illustrated in Fig. 1, will appear from Fig. 2. The selector is of the 15 electro-mechanical type above referred to, the movable contact arms SK of which are adapted to be advanced by the action of a spring KF under the control of holding magnet R . The contact arms SK are carried by a shaft VA and mounted in bearings in the switch frame. Rigidly secured to said shaft is a ratchet segment ST arranged to co-operate with a double holding pawl VH pivotally mounted on a pin HT and 20 actuated by a spring HF . Said pawl is adapted to be operated by one end of the armature MA which is pivoted on an edge MT . The spring KF is fixed at one end to the frame by means of a screw MS and at 25 the other end to a roller FR fixed on the shaft VA . It will be understood from the figure that the contact arms SK are advanced in the direction of the arrow one step upon the magnet R attracting its armature, and another step upon the magnet releasing its armature. After the contact 30 arms have been displaced in this way into the last position, they will be restored to the initial position, which is the first contact position, by means of a lever (not shown in the drawing) swingable about an axis co-axial with the shaft VA and adapted to engage the projection AV of the ratchet segment AT so as to turn the latter back 35 into the initial position.

As seen from Fig. 1, the numerical selector RV has three rows of contacts RK_1 , RK_2 , RK_3 . Arranged to co-operate with these contact rows are three corresponding 40 contact arms consisting of contact springs adapted to connect the opposite contacts of each particular row in each position of the selector.

In the example shown in Fig. 1 the register switches RE are supposed to be constructed in the same way as the numerical selectors, but they are accommodated for only one row of contacts. The different numerical positions of the contact arms are 45 indicated by means of dot-and-dash lines and are designated in the register switches by figures in the order of sequence 1, 2, 3 . . . 0, and in the numerical selectors by figures in the order of sequence 0, 9, 50 8 . . . 1. Between said numerical positions

there are intermediate positions through which the contact arms have to pass for the purpose of the mutual control of the selective operation.

In the system represented in the drawings 70 each junction line FL_1 is provided with a group selector RV serving only to mark the group of junction lines FL_2 to which the connection is to be extended, the connections between the junction lines being established by means of separate connecting apparatus S which in this case are arranged to operate as finder switches. The group selector RV may, contingently, be arranged in 75 known manner in common to a plurality of junction lines. The invention is not limited to systems wherein the numerical selectors form independent switching units separated from the connecting apparatus, as it is readily understood that the invention may 80 be applied also to systems in which the numerical selectors serve at the same time to establish the talking connections.

The switching operations are controlled 85 in known manner by means of sequence 90 switches regulating the order of sequence of the different operations. In Fig. 1 a sequence switch SOG is indicated serving to control a number of contacts SO adapted to be closed in those positions of the sequence 95 switch indicated by numerals placed close to the contacts.

The switching operation is, shortly stated, 100 as follows. When the calling subscriber's line is connected to the junction line FL_1 , the register finder RSG is started whereby 105 a disengaged register equipment REG is connected to the junction line in question. The subscriber then operates his impulse 110 sender thereby causing the relay RS to energize and de-energize alternately, a corresponding number of current impulses being 115 then sent to the register switch RE_1 over the primary register controller PRO in its first position. The register switch RE_1 is 120 thereby set into a position corresponding to the number of current impulses while being advanced one step for each closure of the circuit and another step for each interruption of the circuit. A series of impulses corresponding to the first digit of the number having thus been sent, the register controller PRO will be operated so as to cause 125 the next series of impulses to be received by the second register switch RE_2 which is then set in a similar way. Similarly also the other register switches will be set by the following impulses sent from the subscriber's station.

The starting of the group selector RV 130 takes place immediately after the first register switch RE_1 having been set, the sequence switch SOG being then advanced into its third position in which the magnet R of the group selector is connected in cir-

cuit through the contact SO_2 and through contacts of the register switch RE_1 . At the same time a circuit is closed for a slow-acting relay RST through contacts of the 5 group selector RV in its first position said relay then attracting its armature and causing the sequence switch SOG to be moved into its fourth position. Upon the magnet R attracting its armature, the contact arms 10 of the group selector are advanced into the second position in which a circuit is closed through the holding magnet of the register switch RE_1 , the switch last mentioned being thereby advanced into an intermediate 15 position in which the impulse circuit of the group selector is opened. The group selector will then take another step forward thereby opening the circuit of the register switch which, consequently, will be advanced 20 another step into the next numerical position in which the circuit of the group selector is closed so as to cause the group selector to take another step forward. In this way the switching operation will be 25 going on while breaking and closing the two impulse circuits alternately, until the register switch RE_1 reaches the position following immediately after the last numerical 30 position and in which the magnet of the group selector receives another current impulse before having dropped its armature. The contact arms of the group selector will, consequently, be retained in the corresponding intermediate position. The slow-acting 35 relay RST , which has kept its armature attracted during the setting of the group selector due to the current impulses received through contacts of the contact row RK_2 in every second position of the selector, will 40 now be de-energized. In releasing its armature it closes a circuit through the sequence switch SOG which is thereby advanced into its fifth position. The circuit of the group selector is then opened at the contact SO_2 , 45 and the group selector will, consequently, be moved into the next numerical position in which a circuit is closed through the clutch magnet KM for a number of junction finders S appertaining to the numerical 50 group selected, said junction finders being thereby started simultaneously to search the junction line FL_1 in question. The junction finder which first finds said junction, will establish the connection at the same time 55 causing the other junction finders to be stopped. When the junction finder is connected to the junction line, a circuit is closed over the c -wire of the junction through the slow-acting relay RST which 60 then again attracts its armature and causes the sequence switch SOG to be advanced into the sixth position in which the register equipment REG is connected to the junction line FL_2 through the contacts SO_3 and SO_5 . 65 At the same time the second register controller SRO will be operated to cut off the first register switch RE_1 and to cut in the second register switch RE_2 , the next group selector being then set in a similar way by current impulses which are sent alternately from the register switch to the group selector and from the group selector to the register switch over two corresponding circuits which in this case are carried over the two line branches a and b . After the second group selector having been set, the other group selectors and, finally, the line selector are set in a similar way under the control of the register equipment the switches of which are connected up successively by the controller SRO .

The system shown in Figs. 3-8 differs from the arrangement shown in Fig. 1 by the impulse circuits of the numerical selectors not being controlled by contacts of the register switches but by a control relay RR_3 , Fig. 5, operated from the selector and arranged to control a local circuit of the holding magnet of the register switch. The object of this arrangement is to reduce the 85 number of contacts of the register switches as in this case no contacts are required on the register switches except in their end positions. At the same time the mechanical motion resistance is reduced to such an extent 90 that the register switches will operate equally rapidly and reliably as ordinary relays. The speed of operation will therefore be dependent exclusively on the speed at which the numerical selectors are operating. 95

The primary and secondary register controllers PRO and SRO are of the same construction as the register switches and the numerical selectors. The returning of the contact arms of the register switches and the register controllers to the normal position (the first contact position) is effected by means of a machine driven switch MR , Fig. 5, which serves at the same time as a sequence switch for controlling certain 100 switching operations. The returning of the contact arms takes place, when said switch is moving from its third position back into its first position a rotating arm of the switch then operating the ratchet segments ST , 105 Fig. 2, of the different register switches and controllers in the manner above described, to carry the contact arms into the normal position. The different group selectors RV_1 , RV_2 are restored to normal position in a similar way by the appertaining sequence switches SOG_1 and SOG_2 , respectively. 110

The line finder S_1 and the pre-selectors S_2 , Fig. 3, as well as the junction finders S_3 and S_5 in the different group selecting sections are of the type which has no definite normal position inasmuch as they will be started each time from the position in which 115 they were previously stopped the connec- 120

125

130

tion of a disengaged junction line being effected by the co-operation of several finder switches in such a way that a plurality of switches are started simultaneously to hunt 5 for the junction line in question the connection being established through the switch which first finds said junction. In the example shown the finder switches are of the machine driven type having rotary 10 motion in one direction only. Each finder switch is provided with a clutch magnet KM by means of which the contact arms are coupled in known manner to a continuously 15 rotating shaft.

15 The connecting apparatus S_6 , Fig. 7, of the last connecting section are of the same construction as the other finder switches and are likewise arranged to operate as 20 searchers, the selecting and marking of the subscriber's line wanted being effected by means of separate line selectors LV , Fig. 25 8, which are accessible in common to a group of junction lines FL_4 and provided with finder switches LVS by means of which an idle line selector LV is automatically connected to the junction line in question. Each 30 line selector comprises a tenth selector LV_1 and a unit selector LV_2 which are of the same construction as the group selectors and which are restored to normal position 35 by means of a sequence switch MRV .

The complete switching operation is as follows. Upon a call on the subscriber's line AL , Fig. 3, a circuit 1 is closed as usual 40 through the line relay LR , which in turn closes a circuit 2 through a relay CR , common to all subscribers' lines of the appertaining line group. At the same time a test 45 potential is connected through a contact K_1 to the c -wire of the subscriber's line. Supposing there is no pre-selector connected up to a disengaged junction line at the time, the relay CR will close a circuit 3 through the clutch magnet KM_2 of all accessible 50 pre-selectors S_2 of the group in question said pre-selectors being then started at a time. As soon as a pre-selector finds a disengaged 55 junction line FL_1 , a circuit 4 is established over the d -wire, a relay DR belonging to the pre-selector S_2 in question being then operated to disconnect the clutch magnet KM_2 , whereby said selector is stopped on 60 said junction line FL_1 . The circuit 4 also includes a relay RS_2 , Fig. 4, by which a test potential is connected to the c -wire of the line ML . When the relay DR energizes, a resistance W_1 connected in series therewith will be shortcircuited, whereby the junction line FL_1 is marked as engaged for all other 65 pre-selectors S_2 .

At the same time as the pre-selector S_2 is caused to stop, the corresponding line finder S_1 is started over a circuit 5 including the clutch magnet KM_1 of the line finder. According as other pre-selectors S_2 are con-

nected to disengaged junction lines, the corresponding line finders S_1 will also be started in a similar way. A plurality of line finders may thus be operating all at a time. That one which first finds the calling subscriber's 70 line, will close a circuit 6 through a relay ER appertaining to this line finder, said relay then attracting its armature and opening the circuit of the clutch magnet KM_1 of the line finder, whereby the line finder is 75 stopped. The circuit 6 also includes the subscriber's cut-off relay BR which, in locking itself over a contact K_3 , disconnects the line relay LR whereby also the relay CR is de-energized. The circuits of the other line 80 finders S_1 will, consequently, be opened at the contact K_4 . At the same time the operating circuits of the pre-selectors S_2 which are still working are opened at the corresponding contacts K_5 . Relay ER , upon energizing, will shortcircuit a resistance W_2 connected in series therewith, for the purpose of preventing disturbances by other 85 pre-selectors which may make contact occasionally with the junction line in question. Further, the relay ER will cause a relay GR to be energized whereby the talking line branches will be switched on to the junction line FL_1 , the subscriber's microphone circuit will then be closed through the two windings of a relay RS_1 , Fig. 4, which will keep the relay RS_1 and thereby also the relay ER energized over its contact 7 after the circuit 4 has been opened at the contact 90 K_6 of the relay GR .

The relay RS_1 , upon energizing, closes a circuit 8 through the clutch magnet KM_3 of the sequence switch SOG_1 , whereby the sequence switch is advanced into the second position while being centered in proper position by means of a contact spring KF in well-known manner. In the second position of the sequence switch a circuit 9 is closed including the clutch magnet KM_4 of the register finder RSG , whereby the latter is started to connect the junction line FL_1 to an idle register equipment REG , Fig. 5. Upon the register equipment being connected up, a circuit 10 is closed including a relay RS_6 , Fig. 4, which operates to disconnect the clutch magnet KM_4 of the register finder and to energize a relay RS , over a circuit 11 whereby connection is established between the junction line and the register equipment. At the same time the circuit 12 is closed whereby the sequence switch SOG_1 is advanced into its third position. Said circuit 10 also includes a relay RR_1 , Fig. 5, which operates immediately upon the junction line being connected to the register equipment thereby causing a circuit 13 to be closed through the clutch magnet KM_5 of the sequence switch MR which will then be moved into its second position in which the relay RR_1 receives holding current over the 100 105 110 115 120 125 130 135 140

circuit 14. The relay RR_1 also closes a circuit 15 through a slow acting relay RR_2 , which in turn closes a circuit 16 through the holding magnet IM_1 , of the primary register controller PRO which will thus advance one step. The circuit 15 is thereby opened and the relay RR_2 will therefore de-energize thereby disconnecting the magnet IM_1 and causing the register controller to be advanced one step further. In this position of the register controller a buzzer circuit 13 is closed including a buzzer generator SU and a winding SL of the relay RS_1 , Fig. 4. A calling subscriber will thus obtain a buzzer signal to indicate that the subscriber may now start the sending of the selective current impulses.

When the sequence switch SOG_1 , Fig. 4, was moved into the third position, a circuit 20 18 was closed through a slow acting relay RS_3 , whereby a circuit 19 was closed causing the sequence switch to be advanced into the fourth position, which position the sequence switch will thus occupy, when the subscriber 25 begins to send out the selective current impulses.

When the subscriber now operates his impulse sending apparatus, the circuit 7 will be opened and closed alternately a number of 30 times corresponding to the figure in question of the subscriber's number. The relay RS_1 , Fig. 4 will thus be de-energized a corresponding number of times. The first opening of the circuit 7 causes a circuit 20 to be closed through the relay RR_2 , Fig. 5, which then energizes and operates the register controller PRO so as to cause the latter to be advanced another step, whereby the 35 buzzer circuit is disconnected. At the same time a circuit 21 is closed through the holding magnet RE_1 of the first register switch, whereby said switch is advanced one step. When the impulse circuit is again closed, the 40 circuits 20 and 21 are opened, whereby the first register switch RE_1 will be advanced another step, while the slow acting relay RR_2 , Fig. 5, keeps its armature attracted, thereby maintaining the register controller PRO in the position in which the register 45 switch RE_1 is connected up. It is now readily understood that each of the following impulses will advance the register switch RE_1 two further steps. After the first impulse series has been sent out, the relay RS_1 , Fig. 4, will be maintained energized long 50 enough to allow the relay RR_2 , Fig. 5, to de-energize, whereby the register controller PRO is advanced another step. In this position of the register controller a circuit 22 is 55 closed through the clutch magnet of the sequence switch MR , whereby the sequence switch is advanced into its third position in which a circuit 23 is closed through the holding magnet R_1 of the first group selector switch RV_1 , Fig. 4. The group selector will, conse-

quently, be advanced one step thus closing a circuit 24 through the control relay RR_3 , Fig. 5, which in turn closes a circuit 25 through the register switch RE_1 which is thereby advanced one step. At the same time, however, as the relay RR_3 , Fig. 5, attracts its armature, it will also open the circuit 23 of the holding magnet R_1 , Fig. 4, of the group selector, thereby causing the selector to take another step forward. In this new position of the selector the circuit 24 of the relay RR_3 , Fig. 5, is again opened and, consequently, the circuit 25 will also be opened causing the register switch RE_1 to take another step forward. At the same time, however, the circuit 23 is again closed causing the group selector to take another step forward and to close once more the circuit 24. When, as a consequence, the relay RR_3 again energizes, the register switch RE_1 will receive another current impulse so as to be advanced one step more, while at the same time the circuit 23 is opened, causing the group selector to take another step forward.

In this way the group selector and the register switch will be advanced step by step while mutually controlling each other in such a way, that the group selector cannot take another step forward, until the control relay of the register switch has been energized or de-energized respectively to move the register switch a corresponding step forward. In the meantime the slow-acting relay RS_3 , Fig. 4, is kept energized by the repeated impulses sent through the circuit 18 and the corresponding contacts in every second position of the group selector.

When the register switch RE_1 moves into its last position following immediately after the numerical position designated by the numeral 0, a circuit 26 will be closed over a contact of the relay RR_3 , which is now energized and through the holding magnet R_1 of the group selector. The magnet last mentioned, which just before received a current impulse over the circuit 23, will therefore be prevented from releasing its armature and the group selector will, consequently, be maintained in the corresponding position, which is a position located between two adjacent numerical positions.

At the same time as the register switch RE_1 reaches its last position, also a circuit 27 is closed through the holding magnet IM_2 of the secondary register controller SRO said controller being then advanced into its second position thereby opening the circuit 25 of the register switch. After the switching operation having thus been stopped, while the group selector is in an intermediate position, the slow-acting relay RS_3 , Fig. 4, will be de-energized thereby closing a circuit 28, whereby the sequence switch SOG_1 is advanced into its fifth position. The circuit 24 of the relay RR_3 ,

Fig. 5, is then opened and, upon the de-energization of said relay, the circuits 26 and 27 will be opened. The register controller SRO will thus be moved into the next position in which the holding magnet R_1 of the group selector again receives current over the contact K_7 , whereby the group selector is maintained in the intermediate position in question. The register controller SRO, Fig. 5, however, will now receive another current impulse over the circuit 29, whereby it is advanced another step. In this moment, if the second register switch RE_2 has not yet received all current impulses from the subscriber, the register controller SRO will be retained in the position it is now occupying, through a circuit 30 over contacts of the register controller PRO. As soon as the second register switch has received all the impulses, the primary register controller PRO will, however, be operated in the manner previously described so as to disconnect the register switch RE_2 and to connect up instead of it the third register switch RE_3 for receiving the next series of impulses from the subscriber. The circuit 30 is then also opened and the secondary register controller SRO will, as a consequence, take another step forward thereby opening the circuit of the holding magnet of the group selector. The group selector will therefore be advanced another step and will thus be moved into the numerical position corresponding to the selected group of junction lines FL_2 . Supposing the first register switch RE_1 having been set on the numerical position 7, the group selector will now occupy the position designated by the numeral 8.

When the group selector moves into the position last mentioned, a circuit 31 is closed through the clutch magnet KM_s for all junction finders S_s , Fig. 6, which are disengaged at the time and said junction finders will thus be started. The junction finder which first finds the junction line FL_1 in question closes a circuit 32 including the relay RS_s , Fig. 4, at the group selector RV_1 and a relay RG_1 , Fig. 6, pertaining to the group selector in question. The relay last mentioned energizes and locks itself over a contact 33 while short-circuiting a resistance W_s , whereby the junction line FL_2 is marked as engaged. At the same time the clutch magnet of the junction finder is disconnected and the junction finder will thus be stopped. The relay RS_s , Fig. 4, closes a circuit 34 thereby causing the sequence switch SOG_1 to be moved into the sixth position. At the same time the sequence switch SOG_2 at the second group selector RV_2 , Fig. 6, is advanced into its second position in which the slow-acting relay RG_2 pertaining to said sequence switch is energized over the circuit 36. When the relay

last mentioned attracts its armature, the clutch magnet KM_s of the sequence switch SOG_2 receives another impulse over the circuit 37 whereby the sequence switch is moved into its third position. In this position the group selector RV_2 will now be connected up to the talking line branches of the junction line FL_2 a circuit 38 being then closed through the holding magnet R_2 of the group selector over the b -branch of the talking line. As a consequence, the group selector RV_2 is advanced one step and a circuit 39 is closed over the a -branch of the talking line through the control relay RR_s , Fig. 5, of the register equipment said relay in turn closing a circuit 40 through the holding magnet RE_2 of the second register switch, whereby said switch is advanced one step. At the same time, however, the relay RR_s opens the circuit 38 of the holding magnet R_2 of the group selector so as to cause the group selector to be advanced another step. The setting of the second group selector RV_2 will then proceed alternately with the setting of the register switch RE_2 in the same way as above described with reference to the first group selector RV_1 and the register switch RE_1 , until the register switch RE_2 reaches its end position, when a circuit 41 is closed through the holding magnet R_2 of the group selector RV_2 . The group selector will therefore be retained in the corresponding intermediate position in spite of the control relay RR_s , Fig. 5, being energized in this position thus keeping the circuit 38 open. As the relay RG_2 , Fig. 6, will no longer receive current impulses from the group selector, it releases its armature and closes a circuit 42, whereby the sequence switch SOG_2 is advanced into its fourth position. In this position a circuit is now closed which corresponds to the circuit 31 above described and whereby the junction finders of the second group selecting section (not shown in the drawings) are started similarly as the junction finders S_s of the first group selecting section, the junction line FL_2 being thus similarly connected to the junction line leading to the third group selecting section. The circuit arrangement for the junction finders of the second group selecting section as well as the third group selector and the appertaining sequence switch (likewise not shown) is identical with that shown in Fig. 6. The setting of the third group selector will therefore be effected identically in the same way as described with reference to the second group selector RV_2 , Fig. 6. After the setting of the third group selector has been completed, a circuit 43 will be closed in the same way as above described with reference to Fig. 6. Said circuit actually passes over the third group selector and the appertaining sequence switch not shown, but

its course will appear from Fig. 6 in which the corresponding circuit is designated with the same reference numeral. The circuit 43 in question will cause all junction finders 5 S_5 , Fig. 7, of the third group selecting section which are disengaged at the time, to be started. That one of the junction finders S_5 thus started which first finds the junction line in question, will close a circuit 44 including a relay RV_{11} , Fig. 7, which locks itself over its contact 45, and the relay RG_2 , Fig. 6, which now again energizes and closes a circuit 46, whereby the sequence switch SOG_2 or the corresponding sequence switch 10 of the third group selecting section respectively is advanced into the fifth position in which the talking line is switched on to the line selecting section.

At the same time as the junction finder 20 S_5 is stopped by the energization of the relay RV_{11} , Fig. 7, the sequence switch SOV , Fig. 7, is advanced into its second position by a current impulse over the circuit 47. In this position a circuit 48 is closed through 25 the clutch magnet KM_9 of the selector finders LVS accessible at the time and said selector finders are thus started. The finder which first finds the junction line FL_4 in question, closes a circuit 49 through a relay 30 RV_1 , Fig. 8, which locks itself over a contact 50 at the same time connecting a relay RV_2 in circuit over its contact 51. The relay RV_2 closes a circuit 52 whereby the sequence switch SOV , Fig. 7, is advanced 35 into the third position. In this position a circuit 53 is closed over the b -branch of the talking line and through a relay RV_{14} which operates to open said circuit 52 thereby causing the sequence switch to be stopped in its 40 third position. Just before the relay RV_1 closes a circuit 54 through the clutch magnet KM_{10} of the sequence switch MRV , whereby the latter is moved into its second position. At the same time the relay 45 RV_2 closes a circuit 55 through a slow-acting relay RV_3 corresponding in respect of its action to the relay RS_3 , Fig. 4. The relay RV_3 closes the circuit of a relay RV_4 which connects itself in a holding circuit 50 57. The relay RV_3 also closes a circuit 58 through the holding magnet V_1 of the tenth selector LV_1 . As a consequence, this selector is advanced one step. A circuit 59 is then closed over the a -branch of the talking 55 line through the control relay RR_3 , Fig. 5, of the register equipment. Said relay, in operating, closes a circuit 60 through the holding magnet of the register switch RE_4 whereby the latter is advanced one step. At 60 the same time as the control relay RR_3 , Fig. 5, energizes, the circuit of the relay RV_{14} is opened and, as a consequence, the circuit 58 of the holding magnet V_1 of the tenth selector is also opened, whereby the tenth selector is moved one step further,

thus opening the circuit 59 of the control relay RR_3 , Fig. 5.

In this way the setting of the tenth selector RV_1 will proceed, while at the same time the register switch RE_4 is being stepped 70 forward, until the register switch reaches its end position in which the circuit 61 is closed with a similar result as the above described circuits 26 and 41, the tenth selector being thereby stopped in an intermediate 75 position in which the slow-acting relay RV_3 , Fig. 8, remains de-energized and, as a consequence, it will release its armature. The circuit 58 of the holding magnet of the tenth selector is then opened and the tenth selector 80 takes another step forward into the numerical position corresponding to the figure in question on the subscriber's number. At the same time a circuit 62 is closed through a relay RV_5 which locks itself over a circuit 63 and prepares the connecting up of the holding magnet V_2 of the unit selector LV_2 , the circuit 64 of said magnet being closed when the relay RV_3 , which is now energized over a circuit 65, again attracts its armature. As a consequence, the unit selector will be advanced one step, whereby a circuit 66 is closed over the a -branch through the control relay RR_3 , Fig. 5, which in turn closes a circuit 67 through 90 the register switch RE_5 , the latter being thus advanced one step. At the same time the relay RR_3 opens the circuit 61 of the relay RV_{14} , Fig. 8, which in turn opens the circuit of the holding magnet of the unit selector, whereby the latter is advanced into 95 the next position in which said circuit 66 of the control relay RR_3 is again opened with the same result as previously stated. The setting of the unit selector will proceed, until the register switch RE_5 reaches its end position, in which a circuit 68 is closed, whereby the unit selector is retained in an intermediate position in which the circuit 100 65 of the slow-acting relay RV_3 , Fig. 8, remains open. The relay last mentioned, upon de-energizing, opens the circuit 64, whereby the unit selector is advanced into the numerical position in question.

When the relay RV_3 attracted its armature, a circuit 69 was closed through a relay RV_6 which then connected itself into a holding circuit 70. When the relay RV_3 now again releases its armature, a circuit 71 is closed, including a relay RV_7 . The relay last mentioned locks itself over its contact 72 at the same time closing a circuit 73 of a relay RV_8 which in turn closes a circuit 74 of a tenth relay RV_{10} corresponding to the tenth group to which the desired subscriber 115 belongs. At the same time a circuit 75 is closed through the clutch magnet KM_{11} , Fig. 7, of the connector S_6 , the latter being then started to search the subscriber's line in question. When the connector reaches this 120 125 130

line, a circuit 76 is closed through a relay RV_{15} , Fig. 8, which opens the circuit 75, thereby causing the connector to be stopped. At the same time a circuit 77 is closed 5 through the clutch magnet KM_{12} , Fig. 7, of the sequence switch SOV. Supposing the desired subscriber's line being disengaged, the sequence switch will then be advanced into the fifth position while passing the 10 fourth position in which a testing of the subscriber's line takes place. In passing the fourth position, a circuit 78 is closed through a relay RV_{12} and the cut off relay BR, Fig. 3, of the desired subscriber's line. 15 The relay RV_{12} locks itself over a circuit 79 at the same time marking the desired subscriber's line as engaged by short-circuiting a resistance W_5 . In the fifth position of the sequence switch a circuit 80 is closed 20 whereby the sequence switch is advanced into the sixth position from which the sequence switch will be successively advanced into the ninth position by current through a circuit 81. In passing the sixth, seventh 25 and eighth positions a continuous calling signal is being sent out from a source of calling current RH_1 over a circuit 82. In the ninth position of the sequence switch, on the other hand, an intermittent calling 30 signal is sent out from a source of calling current RH_2 over the contact 83, the signal last mentioned remaining, until the subscriber removes his receiver to answer the call. The calling current passes through a 35 slow-acting relay RV_{13} which, however, is adapted not to be operated by the calling current. On the other hand, it will be operated, when the called subscriber removes his receiver, as the relay RV_{13} will then be 40 passed by current from the central battery. The calling signal sent to the called subscriber may be heard in usual way by the calling subscriber by a buzzer signal being sent over contacts 84 and 85 of the sequence 45 switch from sources of signal current SU_2 , SU_3 through a primary winding SL_2 of a transformer T the secondary windings of which are connected to the talking line branches. 50 When the relay RV_{13} energizes, the sequence switch receives a current impulse over the circuit 86, whereby the sequence switch is advanced into the tenth position in which the talking connection is completed 55 and the sources of signal current are disconnected. 60 Before the called subscriber answers, the microphone circuit of the called subscriber has been prepared in the following way. 65 When the register switch RE_5 , Fig. 5, reaches its end position, a circuit 87 will be closed simultaneously with the closure of the circuit 68, whereby the secondary register controller SRO is moved into its last but one 70 position and, upon the relay RR_3 de-energiz- 75 ing, it will finally be moved into its last position, in which a circuit 88 is closed through the clutch magnet KM_5 of the sequence switch MR. The latter will then be returned 70 into its initial position, thereby causing the contact arms of all register switches and register controllers to be restored into normal position the circuits 14 and 10 are then opened whereby the relays RR_1 , Fig. 5, and RS_6 , Fig. 4, are de-energized. Finally, also 75 the relay RS_7 , Fig. 4, is de-energized, whereby a circuit 89 is closed, causing the sequence switch SOG_1 to be advanced into its seventh position, in which the microphone battery of 80 the called subscriber is connected up through two inductive resistances RS_4 and RS_5 . The resistance RS_4 forms the winding of a relay which will thus energize, when the called subscriber answers. A circuit 90 is then 85 closed, whereby the sequence switch SOG_1 is advanced into its eighth position. When the relay RS_4 energizes, also the disconnecting relay RS_2 receives current over a circuit 91. In the eighth position the sequence switch SOG_1 , also a circuit 92 is closed including the 90 subscriber's meter SM, Fig. 1, which will thus register the call. 95

The restoring of the tenth and unit selectors is effected in the following way. In the fifth position of the sequence switch SOV, Fig. 7, the circuit 49 of the relay RV_1 , Fig. 8, is opened, whereby this relay as well as the relay RV_2 are de-energized. A circuit 93 is then closed through the clutch magnet of the sequence switch MRV, whereby this sequence switch is returned to the initial position, said sequence switch, in returning to normal position, carries with it the contact arms of the tenth and unit selectors, which are thus also returned to normal position. 105

The group selectors RV_1 and RV_2 will remain during the conversation in the position to which they have been previously set and, as a consequence, the circuits 32 and 110 44 are kept closed over the corresponding c-wires, for the purpose of maintaining the talking connection. 115

After both subscribers having restored their receivers at the end of the conversation, the disconnecting relay RS_2 , Fig. 4, will be de-energized the circuit 6 being thereby opened, causing the relays BR, ER and GR, Fig. 3, to be de-energized. Further, the relay RS_2 closes a circuit 94, whereby the sequence switch SOG_1 , Fig. 4, is returned to normal position. At the same time the contact arms of the group selector RV_1 are carried back into normal position by the action of the sequence switch. The circuit 32 is 120 now opened, whereby the relay RG_1 , Fig. 6, is de-energized, and, as a consequence, a circuit 95 will be closed, whereby the sequence switch SOG_2 is restored to normal position, carrying with it the contact arms of the 125 130

group selector RV_2 , which are thus returned into normal position. The circuit 44 is then opened, whereby the relay RV_{11} , Fig. 7, is de-energized and a circuit 96 is closed, causing the sequence switch SOG to be restored to normal position.

In case the called subscriber's line should be engaged, the circuit 78 of the relay RV_{12} , Fig. 7, will not be closed in the fourth position of the sequence switch SOV and the sequence switch will therefore be stopped in the fifth position. In this position the calling subscriber will receive a buzzer signal from a source of buzzer current SU_1 over a contact 97 of the sequence switch. When the calling subscriber restores his receiver, the different switches will be restored and the connection will be severed in the same way as above described.

20 I claim:

1. In a telephone exchange system the combination with a selector and a registering and controlling device, of a selector circuit, means associated with the registering and controlling device for sending impulses over said circuit for the setting of the selector, a register circuit, means associated with the selector for sending back impulses over said register circuit for the setting of the registering and controlling device, said circuits being arranged to control one another mutually so as to cause the impulses to be sent alternately over the selector circuit and the register circuit respectively, and means associated 35 with the registering and controlling device for stopping the selector in a predetermined position.

2. In a telephone exchange system the combination with a selector and a registering and controlling device, of a selector circuit, means associated with the registering and controlling device for sending impulses over said circuit for the setting of the selector, a register circuit, means included in said selector circuit for sending back impulses over said register circuit alternately with impulses over said selector circuit for the setting of the registering and controlling device, and means associated with the registering and controlling device for stopping the selector in a predetermined position.

3. In a telephone exchange system the combination with a selector and a registering and controlling device, of a selector circuit, under the control of the registering and controlling device, a register circuit under the control of the selector, means included in said selector circuit and adapted to send back impulses from the selector to the registering and controlling device for operating the latter, means included in said register circuit and adapted to send control impulses from the registering and controlling device over said selector circuit in response to said back impulses for controlling the operation

of the selector, and means associated with the registering and controlling device for stopping the selector in a predetermined position.

4. In a telephone exchange system the combination with a selector and a registering and controlling device, of a selector circuit under the control of the registering and controlling device, a register circuit under the control of the selector, a stepping magnet of the selector included in said selector circuit and controlling said register circuit so as to send back impulses to the registering and controlling device over the register circuit, means associated with the registering and controlling device and responsive to said back impulses for sending control impulses over said selector circuit to operate the stepping magnet of the selector, and means associated with the registering and controlling device for stopping the selector in a predetermined position.

5. In a telephone exchange system the combination with a selector and a registering and controlling device, of a selector circuit, under the control of the registering and controlling device, a register circuit under the control of the selector, a stepping magnet of the selector included in said selector circuit and controlling said register circuit so as to send back impulses to the registering and controlling device over the register circuit, a stepping magnet of the registering and controlling device responsive to said back impulses and controlling the said selector circuit so as to send control impulses over the selector circuit to operate the stepping magnet of the selector and means associated with the registering and controlling device for stopping the selector in a predetermined position.

6. In a telephone exchange system the combination with a selector and a registering and controlling device, of a selector circuit, under the control of the registering and controlling device, a register circuit under the control of the selector, a stepping magnet of the selector included in said selector circuit and controlling said register circuit so as to send back impulses to the registering and controlling device over the register circuit, a relay responsive to said back impulses and controlling the said selector circuit so as to send control impulses over the selector circuit to operate the stepping magnet of the selector, a relay circuit controlled by said relay and including a stepping magnet of said registering and controlling device, and means associated with the registering and controlling device for stopping the selector in a predetermined position.

7. In a telephone exchange system the combination of a selector having a stepping magnet and an escapement mechanism

- adapted to cause the selector to be stepped forward one step upon the energization of the stepping magnet and another step upon the de-energization of the stepping magnet,
- 5 a selector circuit including said stepping magnet, a registering and controlling device, a register circuit for operating said registering and controlling device controlled by said stepping magnet so as to be closed
- 10 and opened respectively in every second position of the selector, means associated with said registering and controlling device and operating in response to the current impulses in said register circuit to send control impulses through said selector circuit for operating the stepping magnet of the selector.
- 15 8. In a telephone exchange system the combination of a selector having a stepping magnet and an escapement mechanism
- 20 adapted to cause the selector to be stepped forward one step upon the energization of the stepping magnet and another step upon the de-energization of the stepping magnet, a selector circuit including said stepping

magnet, a registering and controlling device comprising a number of register switches having a stepping magnet and an escapement mechanism adapted to cause the register switch to be stepped forward one step upon the energization of the stepping magnet and another step upon the de-energization of the stepping magnet, a register circuit for operating the registering and controlling device controlled by the stepping magnet of the selector so as to be closed and opened respectively in every second position of the selector, means associated with said registering and controlling device and operating in response to the current impulses in said register circuit to send control impulses through said selector circuit for operating the stepping magnet of the selector, and means associated with the registering and controlling device for stopping the selector in a predetermined position.

45 In testimony whereof I affix my signature.

NILS GUNNAR PALMGREN.
